US0D1057335S

(12) **United States Design Patent** (10) Patent No.: **US D1,057,335 S**
(45) Date of Patent: ** Jan. 7, 2025

(54) **MOUNTING COLLAR FOR VACUUM CLEANER BAGS**

(71) Applicant: **LIONSBOT INTERNATIONAL PTE LTD**, Singapore (SG)

(72) Inventors: **Li Lin Loh**, Singapore (SG); **Wai Peng Benjamin Chay**, Singapore (SG); **Tushar Mohan**, Singapore (SG); **Mohan Rajesh Elara**, Singapore (SG); **Dylan Ng Terntzer**, Singapore (SG)

(**) Term: **15 Years**

(21) Appl. No.: **35/519,048**

(22) Filed: **Jun. 21, 2023**

(80) **Hague Agreement Data**

Int. Filing Date: **Jun. 21, 2023**

Int. Reg. No.: **DM/233007**

Int. Reg. Date: **Jun. 21, 2023**

Int. Reg. Pub. Date: **Nov. 17, 2023**

(51) **LOC (15) Cl.** **15-05**

(52) **U.S. Cl.**

USPC **D32/30**

(58) **Field of Classification Search**

USPC D32/30-31

CPC A47L 9/14; A47L 9/1445

Primary Examiner — John R Yeh

(57) **CLAIM**

The ornamental design for a mounting collar for vacuum cleaner bags as shown and described.

DESCRIPTION

1.1 : Front

1.2 : Back

1.3 : Right

1.4 : Left

1.5 : Top

1.6 : Bottom

1.7 : Perspective

1.8 : Exploded reference view

1 Claim, 8 Drawing Sheets
